DESIGN FOR A SHOE SOLE

Gilbert F. Quinn, Beachmont, Mass., assignor to Panther-Panco Rubber Co. Inc., Chelsea,
Mass., a corporation of Massachusetts

Application January 5, 1937, Serial No. 66,894

Term of patent 14 years

To all whom it may concern:

Be it known that I, Gilbert F. Quinn, a citizen of the United States, residing at Beachmont, in the county of Suffolk and Commonwealth of Massachusetts, have invented a new, original, and ornamental Design for a Shoe Sole, of which the following is a specification, reference being had to the accompanying drawing, forming part thereof.

In the drawing, Fig. 1 is a plan view of a shoe sole showing my new design; and Fig. 2 is a cross-section on the line 2—2 of Fig. 1.

I claim:

The ornamental design for a shoe sole substantially as shown.

GILBERT F. QUINN,
